UNITED STATES PATENT OFFICE.

ALFRED KLOTZ, OF MUNICH, GERMANY.

PNEUMATIC INSERTION FOR SHOES.

Application filed June 5, 1922. Serial No. 566,027.

This invention has reference to improvements in arch supports for shoes and relates more specifically to a construction of support in which that portion or area intended to support the broken down foot arch proper can be readily adjusted as regards height and stiffness to suit varying anatomical requirements, and I obtain this result by making the supporting member proper of pneumatic character to be inflated to the required extent by means of an air pump.

Such an adjustable appliance, obviously, has decided advantages over the substantially unyielding and unadjustable devices of similar character now on the market. To slowly accustom the foot to the supporter, the air cushion is at first pumped up but little and is then inflated more and more from day to day until after a time the foot correspondingly has adjusted itself to the fully pumped up cushion. The supporting surface being of soft rubber, the device is entirely comfortable at all times and can readily be kept in sanitary condition by sponging with a suitable liquid.

My invention will best be understood when described in connection with the accompanying drawing, in which Fig. 1 is a plan view of my improved arch supporter, and Fig. 2 a transverse section therethrough.

My foot appliance mainly comprises the slightly arched base plate M, preferably of stiff metal, shaped to fit within a shoe, the intermediate member R, and the inflatable air cell or cushion B, of soft rubber, designed for supporting the hollow of the foot arch and varying in size to conform to different anatomical conditions. This cushion may be secured to the base plate in a variety of ways and I do not confine myself to any one special manner of attachment.

The intermediate member R of practically the size of the air cushion may be of fabric, leather, or other material, and I prefer to extend it along the inner edge to some extent beyond the substantially aligned edges of the base plate and the air cushion to form a flap R₁, and then turn up this extension flap as shown in Fig. 2, to then provide protec-

tion for the cushion against the latter's wearing through by direct frictional contact with the shoe wall. The air cushion is attached to this member R in any suitable manner, preferably by a rubber solution or other adhesive. The intermediate member R may be fixed to the base plate in any suitable manner, for instance by means of rivets N, as shown merely by way of example.

I may also run up the inner edge of the base plate to some extent, as at M₁ in Fig. 2, as a further protection against wear of the air cushion at this most friction-exposed zone. The cushion is wedge shaped in cross-section and its walls, where they converge to form the pointed curved ridge, are inwardly strengthened by a stiffening lining O.

I have provided a special design of valve V for controlling the air content in the cushion, which valve is of relatively flat construction, so as not to unduly protrude on the inside of the cushion and from the lower face of the base plate, as roughly shown in Fig. 2. The valve is permanently secured to the cushion and extends through registering holes in the intermediate layer R and the base plate M to which latter it is locked by a flat nut. The particular construction of this valve forms the subject matter of my U. S. Patent No. 1,536,870, dated May 5, 1925.

What I claim is:—

An arch support comprising a metal base plate, a substantially flat intermediate member fixed to said base plate, an inflatable and deflatable air cushion, having its greatest height at its inner edge, immovably attached to the upper surface of said intermediate member, an upturned flap of substantially the shape of the inner edge of said cushion integrally extending from the inner edge of said intermediate member and permanently attached to the respective cushion edge, and a relatively flat air valve anchored in said metal base plate and extending through the base plate, said intermediate member, and the bottom wall of said cushion.

In testimony whereof I affix my signature.

ALFRED KLOTZ.
